UNITED STATES PATENT OFFICE.

BRUNO TRANKOWSKI AND GUSTAV GRODD, OF BRIDGEPORT, CONNECTICUT.

SELF-MASSAGE ROLLER.

Application filed October 18, 1927. Serial No. 226,854.

Our invention relates to new and useful improvements in a roller form of massage apparatus adapted for hand use on a human body whereby persons may perform a thorough 5 massaging of themselves without any help.

The object of the invention is to provide a roller form of massage device having suitable handles whereby it may be manipulated to good advantage. And, further to include 10 a series of relatively soft rubber rolls, of like construction, each having co-operating means for acting upon the skin of the patient and whereby pressure may be exerted and relieved, followed by suction and skin pricking 15 in a manner to produce a pleasant irritation of the skin and cause a circulation and reaction of blood near the surface.

A further object is to provide a massage roller adapted for self use and which can be 20 used by one or both hands of the operator in a manner to reach any part of the body effectively.

With these and other objects in view, the invention resides and consists in the construction and novel combination and arrangement 25 of parts hereinafter more fully described, illustrated in the accompanying drawings, and pointed out in the claims hereto appended, it being understood that various 30 changes in the form, proportion, size, and minor details of construction within the scope of the claims may be resorted to without departure from the spirit, or sacrificing any of the advantages of the invention.

Similar characters of reference denote like 35 or corresponding parts throughout the several figures of the accompanying drawing forming a part of this specification and upon which—

Fig. 1 shows a side elevation, partly in section, of our improved massage roller.

Fig. 2 is a cross-sectional view through one 40 of the rolls taken on line 2—2 of Fig. 1; and

Fig. 3 is a somewhat similar cross-sectional 45 view taken on line 3—3 of Fig. 1.

Referring in detail to the characters of reference marked upon the drawings, 5—5 represent oppositely disposed handles by 50 means of which the massage roll is manipulated, the said handles being secured to opposite end portions of straight rod 6 that forms a spindle upon which the several rolls 7 turn. These rolls may be substantially alike in construction and are positioned in spaced relation side by side upon the spindle, washers 8 55 being preferably used upon the spindle be-

tween the rolls, and washers 9 are employed between the end rolls and the inner ends of handles 5 as is clearly shown in Fig. 1.

The rolls 7, before mentioned, are preferably formed of comparatively soft rubber and are each mounted upon a short central metal bearing sleeve 10 which is sized to receive and turn upon the spindle 6 as the roller is moved forward or backward, as in use. The several 60 rolls are therefore, free to operate independently according to the method of using the same and obviously the results, in use, depend somewhat upon the amount of force applied 65 in the operation. 70

Referring more specifically to the formation of the rolls 7, it will be noted that they are of a general roll shape, and include a body portion that is secured on the bearing sleeve heretofore mentioned, and has an annular operating surface which for the most part is covered with a series of small outwardly projecting conical-shaped tits 11, that are formed integral with and of the rubber of the 80 rolls. These rolls further include an annular series of pressing bowls 12 having a raised annular edge or lip 13 formed around the outer end portion. These raised projections, as will be seen, are somewhat longer than the tits before mentioned, so as to be 85 effectively compressed when rolled against a body. 85

A further series of sucking bowls 14, (see Figs. 1 and 2) are formed in the peripheral surface of the rolls adjacent to and at each 90 side of the pressing bowls before mentioned. The bowls are also provided around their mouths with a raised edge or lip 15 which being formed of soft rubber readily compresses and conforms to the surface of the 95 skin thereby insuring the desired engagement and effect. Ports 16 serve to connect the side sucking bowl with the pressing bowls 12 and whereby each of the pressing bowls are connected with two side sucking bowls 100 for the purpose of permitting air to pass back and forth therethrough and from one bowl to another. These bowls 12 and 14 each form a radial hole in the roll which serves as an air shaft, the air shaft of the central or 105 pressing bowl being longer than that of the sucking bowl. The three aligned holes are therefore connected one with the other so that when the central one is compressed, which naturally happens when the roller is 110 applied, since their lips are longer, the air will be forced therefrom through the ports

16 and the bowls 14 and until the same become closed by the further application of the rollers. A continued use of the roller causes the skin pricklers 17 within the pressure 5 bowls to engage and rub the skin, followed by the releasing of the bowls, which again expand to their normal shape. The side bowls are released first in the rolling operation, thereby permitting the sucking bowls, in 10 their releasing operation, to draw the air through the ports and in the side or pressure bowls, thereby producing a flow of air in and out of the suction bowls.

From the foregoing, it will be seen that the 15 several rolls are mounted to turn either collectively or independently and each operate independently, so far as its application is concerned. The bowls, as arranged, are laid out in series of three, each series comprising 20 one central pressing bowl and two connected suction bowls, the same being arranged in alignment across the face of the roll so that they are brought into action in quick succession in the manner hereinbefore described.

25 Having thus described our invention, what we claim and desire to secure by Letters Patent is:

1. A massage instrument comprising a supporting spindle provided with handles, 30 rolls rotatably supported thereon, a series of pressing bowls the inlets of which are formed in the periphery of the rolls and having raised annular lips around their outer ends, a series of sucking bowls also arranged in the 35 face of the rolls and having projected annular lip portions, and ports connecting the pressing bowls and the sucking bowls.

2. A massage instrument comprising a supporting spindle provided with handles,

rolls rotatably supported thereon, a series of 40 pressing bowls the inlets of which are formed in the periphery of the rolls and having raised annular lips around their outer ends, a series of sucking bowls also arranged in the face of the rolls and having projected 45 annular lips, the lips of the pressing bowls extending out further than the lips of the sucking bowls, and ports connecting the pressing bowls and the sucking bowls.

3. A massage instrument comprising a 50 supporting spindle provided with handles, resilient rolls rotatably supported thereon, a series of pressing bowls the inlets of which are formed in the periphery of the roll and having raised annular lips formed around 55 their outer end portions, a series of sucking bowls also arranged in the face of the roll and having raised annular lips, ports connecting the pressing bowls and the sucking bowls, and a series of outwardly projected 60 flexible tits formed on the surface of the rolls between the said bowls.

4. A massage instrument comprising a supporting spindle provided with handles, rolls rotatably supported thereon, a series of 65 radially positioned pressing bowls formed in the rolls, sucking bowls formed on either side of the pressing bowls and in alignment therewith, ports leading from the pressing bowls to the sucking bowls, a series of flexible tits 70 on the face of the roll, and a resilient massage tip or finger within some of said bowls.

Signed at Bridgeport, in the county of Fairfield and State of Connecticut this 15th day of Oct. A. D. 1927.
